UNITED STATES PATENT OFFICE.

STEPHEN ALLEY AND JOHN A. MACLELLAN, OF GLASGOW, COUNTY OF LANARK, SCOTLAND.

TURN-TABLE FOR MOLDERS.

SPECIFICATION forming part of Letters Patent No. 397,684, dated February 12, 1889.

Application filed October 5, 1888. Serial No. 287,346. (No model.)

To all whom it may concern:

Be it known that we, STEPHEN ALLEY and JOHN ALEXANDER MACLELLAN, subjects of the Queen of Great Britain and Ireland, residents in Glasgow, in the county of Lanark, Scotland, have invented an Improved Turn-Table to be used by Founders and others, of which the following is a specification.

Our improved turn-table has been designed to be used in connection with rapid-molding apparatus, (such, for example, as that described in the specification accompanying our application for Letters Patent of the United States filed August 29, 1888, Serial No. 284,041,) and it is intended to be placed between the molding apparatus and the place at which the filling of the molten metal into the mold is to be effected. The turn-table is circular and is made with a platform on which workers may stand, with an annular ledge or table on which the mold-boxes are to be carried, and with a central table to carry cores or other articles, such central table being made so as also to serve as a hand-wheel, by means of which the turn-table can be turned.

The constructive details are hereinafter described with the aid of an accompanying sheet of explanatory drawings.

Figures 1 and 2 of the drawings are respectively a plan and a vertical section of the turn-table.

The turn-table is placed partly in a shallow pit, A, being carried by a bed-plate, B, fixed at the center of the bottom of the pit. In the bed-plate B there is fixed a central pillar, C, partly indicated by dotted lines in Fig. 2, and on this pillar there is fitted, so as to be capable of turning on it, a tubular piece, D, forming the main center of the turn-table, the frame-work of which is built upon it and is composed of radial horizontal girders E, of steel or iron, and inclined struts and ties F.

On the frame-work E F there is fixed a platform, G, of sheet-iron. A cylindrical rim, H, is combined with the rest of the frame-work by angle-iron and vertical radial plates J, on which an annular ledge, K, is fixed. This ledge K, which is slightly inclined down toward the center, is provided for receiving the mold-boxes. The center piece, D, is made with a spindle extending above the platform G, and indicated by dotted lines in

Fig. 2, and on this spindle there is set a tubular boss, L, which has fixed at its upper end a small circular table or disk, M, made with 55 a rim, by means of which it can be turned.

On the lower part of the boss L there is a pinion, N, which gears with a spur-wheel, P, on the upper end of a vertical shaft, Q, carried in bearings in the frame-work of the 60 turn-table, and having at its lower end a pinion, R, in gear with a spur-wheel, S, fixed on the stationary central pillar, C. By means of this gearing the entire turn-table is moved slowly round, when the small central table, M, 65 is turned by a worker standing on the platform G.

In using our improved turn-table the mold-boxes are successively transferred from the molding-machine onto the annular ledge K, 70 and the turn-table is moved round at intervals through short distances, a worker on the turn-table putting in cores, if required, and turning the small table M. The mold-boxes being thus carried round step by step, move 75 in succession into the position for filling them, and are carried onward to a position where they are removed or otherwise dealt with.

What we claim as our invention is—

1. A turn-table constructed to turn on a central fixed pillar and comprising, in combination, a frame-work, a platform, a raised annular ledge or table, a central small table adapted to carry cores, &c., and gearing connecting the said central table with the turn-table, where- 85 by a person standing on the turn-table may revolve the latter by turning the central table, substantially as herein set forth.

2. A turn-table with the gearing for turning it, consisting of a central rimmed table or 90 disk, a pinion fixed to the center boss of the table or disk, a vertical shaft carried by the turn-table and having on it a spur-wheel gearing with the said pinion, and a pinion on the vertical shaft gearing with a fixed spur-wheel, 95 substantially as herein described.

In testimony whereof we have signed our names to this specification in the presence of two subscribing witnesses.

STEPHEN ALLEY.
J. A. MACLELLAN.
